UNITED STATES PATENT OFFICE

137,304

DESIGN FOR A FAN

James P. T. Donahue, Oak Park, Ill.

Application December 9, 1943, Serial No. 111,971

Term of patent 14 years

To all whom it may concern:

Be it known that I, James P. T. Donahue, a citizen of the United States, residing at Oak Park, in the county of Cook and State of Illinois, have invented a new, original, and ornamental Design for a Fan, of which the following is a specification, reference being had to the accompanying drawing, forming part thereof.

Figure 1 is a front elevational view of a fan showing my new design, the side of the fan opposite to that shown having the same appearance as the side of the fan appearing in the drawing. Fig. 2 is an edge view thereof.

I claim:

The ornamental design for a fan, as shown and described.

JAMES P. T. DONAHUE.
